UNITED STATES PATENT OFFICE.

HENRY D'OLIER, JR., OF PHILADELPHIA, PENNSYLVANIA, ASSIGNOR TO HOLOPHANE
GLASS COMPANY, OF NEW YORK, N. Y., A CORPORATION OF NEW JERSEY.

SHADE OR REFLECTOR ATTACHMENT.

977,940.

Specification of Letters Patent. Patented Dec. 6, 1910.

Application filed December 8, 1909. Serial No. 531,952.

To all whom it may concern:

Be it known that I, HENRY D'OLIER, Jr., a citizen of the United States, residing in the city of Philadelphia, county of Philadelphia, and State of Pennsylvania, have invented certain new and useful Improvements in Shade or Reflector Attachments, of which the following is a specification.

My invention relates to means for supporting a shade or reflector in proximity to a source of light, and relates more particularly to an attachment for supporting a shade or reflector upon an electrical incandescent lamp socket, particularly when said shade or reflector is comparatively heavy, as when made of glass or other vitreous material.

It is the object of my invention to provide an attachment for the purpose above stated, which shall be simple, cheap to manufacture, easily attachable to the support and reflector, and which shall be capable of making a secure attachment to the reflector irrespective of variations in size or dimensions of such reflector incident to its manufacture.

For an illustration of one of the forms my invention may take, reference is to be had to the accompanying drawing, in which: Figure 1 is a vertical elevational view of an incandescent lamp and its socket, the shade or reflector and its attachment being shown in section. Fig. 2 is a horizontal sectional view taken on the line 2—2 of Fig. 1 showing the attachment in locked or reflector engaging position. Fig. 3 is a similar horizontal sectional view but with the parts in the open position. Fig. 4 is a fragmentary elevational view illustrating means for indicating the relative position of parts.

An incandescent lamp socket S, suitably supported, or hung by electrical conducting cords c, supports an electrical incandescent lamp L in the usual manner. The socket S is provided with a bead b adapted to be engaged by the bead d formed in the upper end of each of a plurality of fingers e of phosphor bronze, hard brass, steel, or any other suitable resilient material. These fingers are riveted at f or otherwise secured to the extension or middle member g, and extend downwardly below the same and terminate in beaded portions h adapted to engage and register with the rim or projec-

tion j, around the upper edge of the glass or other shade or reflector member R.

Supported by and rotatable upon the member g is the lower cam member k having its upper edge turned inwardly and embraced by the member g, the lower edge of the member g being spun or bent over under the flange or lip of the member k, so as to support the member k upon the member g and allow the rotation of the member k with respect to the member g. The periphery of the member k is depressed at m and raised at n, the portions m and n being continuous with each other, and an integral part of the wall of the member k, and so forms a cam for engaging the fingers e to deflect them radially inward to engage the rim or projection j and thus support the shade or reflector R. This clamping movement of the fingers e results from the rotary movement of the member k upon the member g in a counter clockwise direction, as viewed in Fig. 2. At the end of the portion m of the cam there is a more decided depression o serving as a stop to prevent the rotation of the member k beyond the position shown.

In Fig. 3 the parts are shown in the position where the member k has been rotated upon the member g in a clockwise direction so as to allow the fingers e to spring outwardly to release the shade or reflector R.

Rotatable upon the member g and secured thereto by flange and groove engagement is the upper cam member p surrounding the upper ends of the finger e. The structure of this upper member p is similar to that of the lower member k, being provided with cam surfaces in the same manner, so that by rotation of the member p upon the member g the fingers are caused to engage the socket bead b.

The members g, k, and p are preferably made of brass, or other sheet metal, though any suitable material will serve and may be formed by spinning or any other suitable process and the cams formed by dies or any other suitable means. The fingers e may be of the same material as member g, but preferably of thicker and more resilient material than member g.

As shown in Fig. 4, the member g may have a mark r thereon which, when the ring k is in the unlocked position, registers with or comes opposite to the mark r upon the

ring *k*. When these marks are opposite each other to indicate unlocked position, the arrow will indicate the direction of movement of the part *k* to produce the locking or 5 clamping action.

While I have here shown the cams to be parts of the walls of the members *k* and *p*, it is to be understood that these members may have secured upon them suitably shaped 10 pieces of metal to form a cam or wedge to accomplish the same purpose.

By the foregoing construction a strong attachment is formed for supporting a shade or reflector, particularly when of glass or 15 other vitreous material in the manufacture of which irregularities in outer diameter of the rim or bead *j* are likely to occur. Because the fingers *e* are of sufficient strength and capable of sufficient radial movement, 20 these irregularities do not prevent the shade or reflector being firmly gripped and held.

While I have here shown one form of my invention, it is to be understood that my invention comprehends also other structures 25 wherein cam or wedging action takes place upon suitable fingers to clamp the attachment to the shade or reflector member or to clamp the same to a socket or other support.

What I claim is:

- 30 1. In an attachment, the combination with a finger supporting member, of a finger separate therefrom and secured thereto and extending lengthwise of said supporting member within the same, and a finger actuating member supported upon and rotatable always in the same plane upon said finger supporting member, said finger actuating member when rotated upon said supporting member engaging said finger to deflect the same.
- 35 2. In an attachment, the combination with a finger supporting member, of a separate finger extending lengthwise thereof within said member and secured thereon, a finger actuating member supported upon and rotatable always in the same plane upon said finger supporting member, and a cam carried by said finger actuating member for engaging said finger to move the same into engaging position.
- 40 3. The combination with a lamp socket, of a finger supporting ring, a socket engaging finger supported within and by said finger supporting ring and extending lengthwise thereof, a finger actuating ring having a lip and groove connection with said finger supporting ring at one edge thereof and depending therefrom and rotatable with respect thereto for moving said finger into engagement with said lamp socket.
- 45 4. The combination with a lamp socket, of a finger supporting ring, a separate finger secured upon said finger supporting ring, a finger actuating member having a lip and groove connection with said finger supporting ring at one edge thereof and depending

therefrom and rotatable with respect thereto, and a cam on said finger actuating member for engaging said finger beyond said finger supporting ring.

5. The combination with a lamp socket, of 70 a finger supporting ring, a plurality of separate fingers secured to said finger supporting ring and extending lengthwise of said finger supporting ring, a shade or reflector, said fingers adapted to engage said lamp socket 75 and said reflector at their opposite ends, and rotatable cam members supported by said finger supporting ring and movable with respect thereto always in the same plane for causing said fingers to engage said socket 80 and said shade or reflector.

6. In an attachment, the combination with a finger supporting ring, of a plurality of separate fingers secured to and extending lengthwise of and beyond said finger supporting ring, a finger actuating ring supported and rotatable always in the same plane upon said finger supporting ring, at one end thereof, said finger actuating ring surrounding said fingers beyond said finger 90 supporting ring.

7. In an attachment, the combination with a finger supporting ring, of a plurality of separate fingers secured to and extending lengthwise of and beyond said finger supporting ring, a finger actuating ring supported and rotatable always in the same plane upon said finger supporting ring, at one end thereof, said finger actuating ring surrounding said fingers beyond said finger 95 supporting ring, and cams on said finger actuating ring for engaging said fingers.

8. In an attachment, the combination with a finger supporting ring, of a finger actuating ring having a lip and groove connection with said finger supporting ring at one end thereof and extending beyond the same, and fingers supported upon said finger supporting ring and extending lengthwise thereof and beyond the same into said finger actuating ring.

9. A shade or reflector attachment comprising a finger supporting ring, a finger supported upon said ring and extending lengthwise thereof, a finger actuating ring supported upon one edge of said supporting ring and extending beyond the same and rotatable always in the same plane upon said finger supporting ring, and a cam on said finger actuating ring beyond said supporting ring and extending partially within and partially without the normal contour of said actuating ring for engaging said finger.

10. In an attachment, the combination with a finger supporting ring, of a finger actuating ring having a lip and groove connection with said finger supporting ring at one end thereof, fingers supported upon said finger supporting ring and extending lengthwise of and beyond the same into said finger 125

actuating ring, and cams on said finger actuating ring for engaging said fingers beyond said supporting ring.

11. In an attachment, the combination with a finger supporting ring, of a plurality of fingers supported thereby and extending lengthwise thereof, a finger actuating member supported upon and rotatable always in the same plane upon said finger supporting ring, and cam surfaces struck up from the material of said finger actuating ring for engaging said fingers.

12. The combination with a finger supporting ring, of fingers supported thereby and extending lengthwise thereof and beyond the same, a finger actuating ring rotatable always in the same plane upon said finger supporting ring and extending beyond said finger supporting ring and sur-

rounding said fingers, and a cam for each 20 of said fingers integral with said finger actuating ring.

13. In a device of the character described, a finger supporting ring, fingers supported thereon, a finger actuating ring supported upon said supporting ring, and a cam immovable with respect to said finger actuating ring and integral therewith and extending partially within and partially without the normal outer contour of said finger actuating ring.

In testimony whereof I have heretounto affixed my signature in the presence of the two subscribing witnesses.
